Primary Examiner — Paula Allen Greene(74) *Attorney, Agent, or Firm* — Brooks Kushman P.C.(57) **CLAIM**

The ornamental design for an earphone component, as shown and described.

DESCRIPTION

FIG. 1 is a perspective view of an earphone component according to an embodiment;

FIG. 2 is a right side view of the earphone component;

FIG. 3 is a left side view of the earphone component;

FIG. 4 is a rear side view of the earphone component;

FIG. 5 is a front side view of the earphone component;

FIG. 6 is a bottom side view of the earphone component; and,

FIG. 7 is a top side view of the earphone component.

The broken lines depict environment that forms no part of the claimed design.
